UNITED STATES PATENT OFFICE.

HAMILTON C. STUART, OF ST. JOHNSBURY, VERMONT.

FIRE-BOX.

1,223,441.

Specification of Letters Patent. Patented Apr. 24, 1917.

Application filed September 29, 1916. Serial No. 122,899.

To all whom it may concern:

Be it known that I, HAMILTON C. STUART, a citizen of the United States, residing at St. Johnsbury, in the county of Caledonia and State of Vermont, have invented certain new and useful Improvements in Fire-Boxes, of which the following is a specification.

This invention relates to an improved stove and the principal object of the invention is to provide a stove having an improved construction whereby fuel of a liquid nature may be placed in a pocket formed in a housing having communication with the fire box and fuel placed in the fire box thus ignited by the fuel burning in the pocket.

Another object of the invention is to so construct the housing in which the fuel holding pocket is formed, that it may constitute a draft inlet for the fire box of the stove.

Another object of the invention is to provide an improved type of wick, for igniting fuel placed in the pocket.

This invention is illustrated in the accompanying drawings, wherein:

Figure 1 is a fragmentary sectional view through a portion of a stove provided with the improved construction.

Fig. 2 is a perspective view of the wick. The stove indicated in general by the numeral 10 is provided with a fire box 11 positioned above the ash pit 12 and provided with the usual grate 13. This grate 13 is positioned upon a level with the housing 14 which is formed in the jacket or shell of the stove and provided with an opening 15 permitting communication with the interior of the fire box 11. Therefore draft may pass through the opening 15 into the fire box.

Within this housing 14 there is provided a cross strip forming a wall 16 for the fuel pocket or pan 17. The liquid fuel which is preferably oil is placed in the pan 17 and will be ignited by means of the wick 18 which is positioned in the oil pan and con-

nected with the wall 16 by means of the clamping plate 19 held in engagement with the walls 16 by clamping arms 19'. When this wick is ignited, the flame will be drawn toward the opening 15 and the heat will vaporize the oil in the receptacle 17, the vapors igniting and the flame passing through the opening 15 and into the fire box. This flame will ignite the coal or other fuel placed in the fire box of the stove and the fire in the stove can thus be started in a very short length of time. It will thus be seen that this structure provides a fire starter in which the oil can be placed in front of the draft opening of the fire box.

What is claimed is:

1. A stove including a jacket and a fire box, the jacket being provided with a housing having in its inner wall an opening permitting communication with the fire box, a cross strip in the housing forming a liquid fuel receptacle in the inner portion of the housing, a wick positioned in the liquid fuel receptacle against the cross strip, a securing plate engaging said wick, and clamping arms extending from the plate and engaging said cross strip to releasably hold the wick in place.

2. A stove including a jacket and a fire box, the jacket being provided with a housing having an opening in its inner walls to permit communication with the fire box, a strip extending across the housing to provide a liquid fuel receptacle in the inner portion thereof, a wick in said receptacle fitting against said strip, and means for releasably holding the wick in engagement with the cross strip.

In testimony whereof I affix my signature in presence of two witnesses.

HAMILTON C. STUART.

Witnesses:

ROY N. HOWARD,
JOHN T. RITCHIE.
